UNITED STATES PATENT OFFICE.

ERNEST D. SMITH, OF LOCKHART, TEXAS, ASSIGNOR OF ONE-HALF TO
FRANCIS L. HILLYER, OF LOCKHART, TEXAS.

BALING-PRESS.

SPECIFICATION forming part of Letters Patent No. 750,232, dated January 19, 1904.

Application filed June 15, 1903. Serial No. 161,570. (No model.)

To all whom it may concern:

Be it known that I, ERNEST D. SMITH, a citizen of the United States, residing at Lockhart, in the county of Caldwell and State of Texas, have invented a new and useful Baling-Press, of which the following is a specification.

This invention relates to certain improvements in hay-presses, and has for its principal object to provide a simple, economical, and powerful form of press for the condensing of hay and other materials into the form of bales or bundles.

One object of the invention is to provide a device of this character in which a system of toggle-levers is so connected to the press-plunger that the necessary compressing force may be obtained from a single animal without unnecessary strain on the animal or on any of the parts of the apparatus.

A further object of the invention is to construct a plunger-operating mechanism in which the horse-power, preferably of sweep-like form, effects the operation of the plunger twice during each rotation of the sweep, and in which provision is made for automatically disengaging the horse-power from the plunger-operating levers as soon as the latter have reached the full limit of the compression-stroke.

A still further object of the invention is to provide a device of this character in which the compression-levers are positively returned to an initial position and the plunger positively withdrawn to the limit of its outstroke by automatic engagement of the horse-power with said levers.

With these and other objects in view, as will hereinafter more fully appear, the invention consists in the novel construction and arrangement of parts, hereinafter described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a plan view of a hay-press constructed in ac-

cordance with the invention and illustrating the plunger at the limit of its outstroke. Fig. 2 is a similar view showing the plunger at the limit of its compression-stroke. Figs. 3 and 4 are detail views more specifically referred to hereinafter.

55

Similar numerals of reference are employed to indicate corresponding parts throughout the several figures of the drawings.

In the drawings, 1 indicates the compression chamber or box, which may be of the usual construction and provided with a plunger 2 of any ordinary character.

3 indicates a frame formed of a pair of sills, the outer ends of which are connected to a cross-bar 4, and said sills, in connection with the cross-bar, serve as supports for a vertically-disposed pin or stud 5, to which the outer end of the system of toggle-levers is connected. As it is intended that the device shall be easily handled and transported from place to place, the compression-chamber ends of the sills are provided with recesses 6, and the lower sills or supports 7 of the compression-chamber are also provided with recesses 8, each recess receiving a projecting portion of one of the adjacent frame members in order to prevent their longitudinal separation during the operation of the press, while permitting ready detachment of the power-head and horse-power from the compression-chamber in order that the two members may be conveniently loaded on a wagon or truck for transportation. The two sills 3 are connected together at an intermediate point by cross bars or planks 9 and 10, which serve to support the pivot-pin 85 of the power-head, while the bar or plank 10 is extended for a considerable distance on each side of the sills, and its upper face is covered in part with iron sheathing to form a suitable rest and support for a portion of the toggle mechanism.

The two main levers 12 and 13 of the toggle are connected, respectively, to the plunger 2, and the pivot-pin 5, and said levers are pivotally connected to each other by a pin or stud 14, on which is also hung the intermediate bar 15, which connects the toggle to the horse-power, and longitudinal movement imparted

to this intermediate bar 15 in one direction will tend to move the plunger inwardly into the press-box to effect the compression-stroke, while the movement in the opposite direction tends to withdraw the plunger and return the toggle-levers to an initial position.

The horse-power comprises a horizontally-disposed bar 16, pivoted at a central point on the pin or stud 11 and furnished with two angularly-disposed sweep-arms 17, which at their outer ends are connected together and serve to support a swingletree 18, to which the animal may be harnessed. Near each end of the bar 16 are depending pins or lugs 19, which when in proper position engage alternately with a hook 20, carried by the inner end of the bar 16, and said hook is at all times held in proper position to be engaged by the pins by means of a suitable tension-spring 21, connecting the outer portion of bar 15 with one of the toggle-levers 12. In the operation of this portion of the mechanism the rotative movement of the sweep will bring one of the pins 19 into engagement with the hook 20, and as rotative movement is continued the toggle-levers will be drawn to the position shown in Fig. 2, being nearly or quite in alignment with each other and exerting considerable force on the plunger to compress the material previously inserted in the press-box. As the parts approach the limits of effective movement the pin will tend to separate from the hook, and to permit this movement the hook is provided with a bill extending practically at a right angle to the length of the bar 15, so that the pin may slide freely from said hook. To insure the positive disengagement of the pin from the hook and the return of the toggle-levers to initial position, as well as to prevent the sweep from coming into contact with the legs of the animal, I employ a pair of pivoted arms 24 and 25, one of which is pivoted to one of the sills 3, while the other is pivotally connected to the toggle-lever 13. These two bars are pivotally connected at their outer ends, and projected from the end portion thereof is a finger 26, which at the limit of compression movement is disposed in the path of bar 15, contact of the bar 15 with said finger serving to positively disengage the hook. As soon as this is accomplished the bar 16 engages a finger 27, also disposed at the outer ends of arms 24 and 25, and rotative movement of the bar 16 is then transmitted through arm 25 and tends to force the toggle-levers to return to initial position. This engagement of the parts prevents any sudden movement of the sweep when the hook is disengaged from the pin and prevents contact of the sweep with the legs of the animal. The arrangement of the arm 24 is such as to gradually disengage finger 27 from the bar 16, so that it will be impossible to break or strain any of the parts.

The spring 21 is employed to hold the bar

15 in such position that its hook shall at all times be in readiness to be engaged by one of the pins 19.

The length of the toggle-levers is such as to render it unnecessary to employ very heavy or expensive arms or connections, while the movement of all of the parts is positive in its character and the levers are so proportioned that great pressure may be exerted without undue strain on the animal.

Having thus described the invention, what is claimed is—

1. The combination in a baling-press, of a compression-box and plunger, a system of toggle-levers connected to the plunger and including an intermediate operating-bar, a horse-power, means for connecting the horse-power to the intermediate bar, and means carried in part by the toggle mechanism for positively disengaging such connecting means at the limit of the compression-stroke. 85

2. The combination in a baling-press, of a compression-box and plunger, a system of toggle-levers operatively connected to the plunger and including an intermediate bar, a hook member carried by said bar, a revolute horse-power including a pivotally-mounted bar, pins carried by the opposite end portions of said pivotally-mounted bar and adapted to engage the hook member, means operable in part by the toggle mechanism for positively disengaging the hook at the limit of each compression-stroke. 90

3. The combination in a baling-press, of a compression-box and plunger, a system of toggle-levers operatively connected to the plunger, a horse-power, means for connecting the horse-power to the toggle mechanism, a pair of bars pivotally connected at one end and at their opposite ends connected respectively to a fixed point and to one of the toggle-levers, the pivotally-connected ends of said bars being moved during the compression-stroke to a position to effect the disengagement of the means for connecting the horse-power and toggle mechanism. 100 105 110

4. The combination in a baling-press, of a compression-box and plunger, a system of toggle-levers operatively connected to the plunger, a horse-power, means for connecting the same to the toggle mechanism, means for disconnecting the toggle mechanism and horse-power at the limit of the compression-stroke, consisting of a pair of pivotally-connected bars of which one is connected to one of the toggle-levers, the connected ends of the bars being disposed in the path of movement of the horse-power. 115 120 125

5. The combination with a baling-press including a compression-box and plunger, of a toggle mechanism operatively connected to the plunger and including an intermediate bar, a revolute sweep, a pin or lug carried by a portion of the sweep, a hook member car-

ried by the intermediate bar of the toggle and adapted to be engaged by the pin or lug, a pair of pivotally-connected bars of which one is pivoted to a fixed point and the other to one of the toggle-levers, and a pair of fingers carried by said bars and disposed one in the path of movement of the hook and the other in the path of movement of the sweep, said fingers serving respectively to release the hook and to operatively connect the toggle mechanism

to the horse-power and return the parts to initial position.

In testimony that I claim the foregoing as my own I have hereto affixed my signature in the presence of two witnesses.

ERNEST D. SMITH.
